UNITED STATES PATENT OFFICE.

ROBERT RENTON GIBBS, OF LIVERPOOL, ENGLAND.

HOT-WATER-CIRCULATING APPARATUS.

SPECIFICATION forming part of Letters Patent No. 621,999, dated March 28, 1899.

Application filed April 18, 1898. Serial No. 678,003. (No model.)

To all whom it may concern:

Be it known that I, ROBERT RENTON GIBBS, a subject of the Queen of Great Britain, residing at Liverpool, in the county of Lancaster, England, have invented certain new and useful Improvements in Hot-Water-Circulating Apparatus, of which the following is a specification.

In hot-water-circulating apparatus for heating purposes, in which there is a pipe or pipes for conveying the hot water from the boiler to the various parts of the building that require heating and which is amplified into coils at special points, it has been usual to provide such apparatus with an expansion-chamber, in which the water can expand as it becomes heated, or with an open cistern in which the water rises or falls. The use of this expansion-chamber is inconvenient in many cases, because, besides being an unsightly object, it is often difficult to find suitable space to fix it in, and the defect of an open cistern is that it is liable to boil over and so flood the building.

Now the object of my present invention is to provide a hermetically-closed hot-water heating or circulating system, in which the usual expansion-chamber of the open tank can be entirely dispensed with.

The invention will be understood from the following description, reference being had to the accompanying drawing, which shows a general view of the apparatus.

Referring to the drawing, I provide an ascending pipe A, leading from the boiler B to radiators C, which are located at suitable points in the building—such as, for example, on the various stories—and descending pipes D, by which the water again reaches the furnace, the whole circuit being hermetically sealed or closed. These radiators, which are closed vessels, may be of any suitable construction, so as to provide a large heat-radiating surface, and they form part of the hot-water circuit, deriving their heat by the hot-water pipes aforesaid from the boiler B. One or more of these radiators—namely, the ones at the highest elevation—are used to take the place of an expansion-chamber, such radiator or radiators being only partly filled with water, so as to leave the upper portion empty

for the water to expand in as it becomes heated. For this purpose I arrange in proximity to those radiators, which are used as substitutes for an expansion-chamber, a stand-pipe E, which is cut short of the full height of the said radiators. The effect of pouring water into the stand-pipe will be to fill the circulating-pipes and all the radiators, with the exception of those at the highest elevation, 60 completely full of water. Those, however, at the highest elevation will only be partly filled to a certain level, because the stand-pipe, being cut short of the full height of the radiators, prevents the latter being filled 65 higher than the top of the stand-pipe. This insures the said radiators not being filled to the top, the area of the empty space for the expansion being proportioned to the length of the circuit and the number of radiators 70 therein. Instead of a stand-pipe, however, a metal or other bend may be screwed into the side of the expansion-radiator at a certain distance short of the top, through which water can be fed into the circuit. Means are provided, such as a cap or cock, for closing the mouth of the bend or stand-pipe, so that the entire circuit may be a hermetically-closed 75 one.

A relief-valve F or other device may be provided in the upper part of the expansion-radiator or any part of the system, if so desired, so as to provide against the accumulation of dangerous pressure; but such is not necessary if the apparatus is properly proportioned.

A convenient form of radiator is that in which there is a series of sections or chambers joined together top and bottom and through which the hot water follows a winding path 90 in such manner as to provide a large heat-radiating surface.

I declare that what I claim is—

1. In a hot-water-circulating apparatus, the combination of a water-heating device; a radiator; pipes connecting the same into a single closed circuit; and a closable orifice placed in the circuit and having its mouth a little below the highest point of the radiator, whereby the upper part of the radiator cannot be 100 filled but acts as an expansion-chamber.

2. The combination of the boiler B; ascend-

ing pipe A; radiators C; descending pipes D,
the whole forming a closed circuit; and stand-
pipe E opening into the circuit and having its
mouth a little below the top of the highest
5 radiator, substantially as and for the pur-
poses described.

In witness whereof I have hereunto signed

my name, this 7th day of April, 1898, in the
presence of two subscribing witnesses.

ROBERT RENTON GIBBS.
